UNITED STATES PATENT OFFICE.

JAMES ALBERT GARLAND, JR., OF NEWTON, MASSACHUSETTS.

DESIGN FOR A GAME-BOARD.

SPECIFICATION forming part of Design No. 25,449, dated April 28, 1896.

Application filed December 23, 1895. Serial No. 573,112. Term of patent 3½ years.

To all whom it may concern:

Be it known that I, JAMES ALBERT GARLAND, Jr., a citizen of the United States, residing at Newton, (Chestnut Hill,) in the county of Middlesex and State of Massachusetts, have invented and produced a new and original Design for Game-Boards, of which the following is a specification, reference being had to the accompanying drawings, forming part thereof, in which—

Figure 1 is a plan view of the board, showing my design; Fig. 2, a section thereof on lines 2 2; and Fig. 3 is a section on line 3 3, these three figures being necessary to fully illustrate my design.

The leading feature of my design consists of a circular game-board, in which is formed a central circular cavity or depression B, the bottom of which is broken or irregular and 20 in which are formed a number of elevations, as shown at C, D, E, G, II, K, L, and M, and the sides thereof slope from the top portion downwardly in irregular form, and the bottom of the game-board between said elevations is also irregular in form, portions thereof being higher than others, and the elevations D, G, and K are provided with branches 25 d, g, and k, respectively, which form narrow passages, and the tops of said elevations, with the exception of the elevation M, are also level or even with the top of the game-board. The elevation K is also circular in form, and

formed in the bottom of the game-board at the right thereof or between said elevation and the elevation II is a circular cavity or 35 depression n.

All the higher elevations, with the exception of the elevation G and its branches, project inwardly from the rim of the board and are irregularly curved, as shown, and the 40 branches of the elevation G project outwardly and are also irregularly curved, and by this means it will be seen the plan of the game-board is regular in form and the central cavity or depression broken or divided 45 by the said elevation into numerous spaces, which are also irregular in form, and the bottoms of which are uneven and of different heights, and within the game-board is placed a spherical body or ball O.

Having fully described my new and original design for game-boards, what I claim, and desire to secure by Letters Patent, is—

The design for a game-board, substantially as herein shown and described.

In testimony that I claim the foregoing as my invention I have hereunto signed my name, in the presence of two witnesses, this 21st day of November, 1895.

JAMES ALBERT GARLAND, JR.
